UNITED STATES PATENT OFFICE.

GEORGE M. HAYES, OF PHILADELPHIA, PENNSYLVANIA.

DESIGN FOR A CARD.

SPECIFICATION forming part of Design No. 13,254, dated August 22, 1882.

Application filed July 13, 1882. Term of patent 3½ years.

To all whom it may concern:

Be it known that I, GEORGE M. HAYES, a citizen of the United States, residing in the city and county of Philadelphia, State of Pennsylvania, have invented and produced a new and original Design for Cards, of which the following is a specification, reference being had to the accompanying photographic illustration, forming part thereof.

10 My design consists of a card of the form of a whisk-broom, the head of which is covered by a cap, *a*, the face of the cap being ornamented by a picture, *b*. A cord, *c*, is attached to the handle and hangs as a loop on the cap *a*, and a cord, *d*, surrounds the picture *b*, simulating a frame therefor, thus forming a unique, 15 graceful, and attractive card.

I claim—

1. The design for a card of the form of a whisk-broom, with a picture on the face thereof, substantially as shown and described. 20
2. The design for a card of the form of a whisk-broom, with a picture surrounded by a cord, as a frame therefor, substantially as shown and described. 25
3. The design for a card of the form of a whisk-broom, having a cap on its head, a looped cord attached to its handle, and a picture on the face of the cap, substantially as shown and described.

GEO. M. HAYES.
